HANDLE FOR A REFRIGERATOR CRisper DRAWER

Robert D. Strub, Coralville, Iowa, and Kenneth P. Schory,
Bensenville, Ill., assignors to Amana Refrigeration, Inc.,
Amana, Iowa, a corporation of Iowa

Application April 9, 1957, Serial No. 45,649

Term of patent 3½ years

(Cl. D67—3)

Figure 1 is a perspective view of a handle showing our new design;

Figure 2 is a front elevation thereof;

Figure 3 is a vertical section taken on line 3—3 of Figure 2;

Figure 4 is a vertical section taken on line 4—4 of Figure 2; and

Figure 5 is a vertical section taken on line 5—5 of Figure 2.

The broken line showing of a portion of a refrigerator crisper drawer is for illustrative purposes.

We claim:

The ornamental design for a handle for a refrigerator crisper drawer, substantially as shown and described.
